Patented July 30, 1918.

UNITED STATES PATENT OFFICE.

WILLIS K. MILLER, OF CARLISLE, PENNSYLVANIA.

UMBRELLA.

1,274,305.

Specification of Letters Patent. Patented July 30, 1918.

Application filed June 20, 1917. Serial No. 175,884.

To all whom it may concern:

Be it known that WILLIS K. MILLER, a citizen of United States, residing at Carlisle, in the county of Cumberland and State 5 of Pennsylvania, have invented new and useful Improvements in Umbrellas, of which the following is a specification.

This invention relates to umbrellas, and has particular reference to umbrellas of the 10 folding or collapsible type.

The primary object of the invention is to provide an umbrella wherein the main frame elements thereof are of a telescopic and folding nature, whereby when the umbrella is 15 not in service the same may be compactly collapsed so as to occupy but a minimum of storage space.

Another object of the invention resides in an umbrella of the above character, which, 20 when collapsed can be readily received by an average sized traveling bag or the like, in order to facilitate in carrying or transporting the umbrella.

A further object resides in an umbrella 25 embodying these desirable features, which will be simple to operate, of strong and substantial construction, light in weight and inexpensive to manufacture.

With these and other objects in view, as 30 will appear as the description proceeds, the invention consists in the novel features of construction, combination of elements and arrangement of parts hereinafter fully set forth in the following description, the scope 35 of which being indicated by the appended claims.

In the drawing—

Figure 1 is a side elevation, partly in section, of an umbrella frame embodying the 40 features of the present invention.

Fig. 2 is a similar view showing the frame in a collapsed position.

Fig. 3 is an enlarged vertical sectional view showing the internal construction of 45 the lower sections of the umbrella staff, and the coöperating runner.

Fig. 4 is a similar view, illustrating the upper and lower sections of the staff in a collapsed position.

Fig. 5 is an enlarged sectional view of the 50 rule joint construction of the folding rib members, and their associated parts, and

Fig. 6 is a detail transverse sectional view, taken along the line 6—6 of Fig. 5.

Fig. 7 is a detail transverse sectional view, 55 taken along the line 7—7 of Fig. 5.

staff 1, the latter being formed of a plurality of telescopic sections 2 and 3, the section 2 forming the upper and outer section and the section 3 the lower or inner section. 60 A handle section 4 is detachably secured to the lower end of the inner section 3, by providing the latter with a spring-actuated thumb catch 5 which, when the handle section is passed over the lower extremity of 65 said inner section, will engage with a slot 6 formed in the upper end of the handle section, so that the accidental disengagement of the sections 3 and 4 will be effectively prevented. The lower end of the section 3 70 fits tightly within the upper tubular end of the section 4, thereby providing a rigid and substantial connection between said sections. The lower end of the handle section may, of course, be formed in any preferred 75 manner.

Slidable over the inner section 3 is a runner 7, which is provided with the usual ring 8 for pivotally securing the inner extremities of braces 9 to the runner. The outer extremities of the braces are pivotally connected with sliding tubular elements 10, movable over the cover-carrying ribs 11 of the umbrella. The ribs in turn have their inner extremities pivotally associated with a 80 fixed ring 12, carried upon the upper end of the section 2. Thus when the runner is moved upwardly upon the section 3, the ribs will be extended to open the umbrella, and conversely, upon the downward movement of 85 the runner the ribs will be oscillated to a folded position, as is common in umbrella construction.

The runner 7 is capable of being retained in its lowermost position by providing the 90 same with an annular shoulder 12^a, which is adapted to coöperate with a locking catch 13, carried by the section 3.

The catch includes a resilient shank portion 14, secured within the tubular interior 100 of the section 3, and terminates in an enlarged runner-engaging extremity, which protrudes through a slot 15 formed in said lower section, whereby when the runner is retracted said extremity will engage with the 105 shoulder 12^a to prevent uncontrolled movement on part of said runner. A leaf spring 16, mounted within the section 3, engages with the catches 5 and 13, and serves to augment the resiliency of the latter. The runner 110 7 may be released from engagement with the catch 13, by providing the latter with

an offset thumb-engaging lug 17, the latter extending exteriorly of the section 3 so as to be conveniently manipulated by the thumb of an operator. By depressing the lug the catch 13 will be moved inwardly, thus releasing the runner so as to permit the latter to be elevated.

A resilient latch 18 is securely mounted within the section 3 contiguous to the upper 10 end of the latter, and is provided with an enlarged portion, which extends through a slot formed in said section. Thus when the runner is fully elevated, so as to extend the ribs 11, said latch will automatically engage with the under edge of the shoulder 12^a so as to retain the runner in its elevated position. The resiliency of the latch is aided by use of a leaf spring 19 mounted within the section 3. To release the runner from engagement with the latch 18, the latter is pressed inwardly so that it will clear the runner, thus permitting the latter to be readily retracted.

The outer or upper end of the section 3 is 25 provided with a second latch 20, which is similar in construction and operation to the latch 18, and is provided with an enlarged portion, which extends through a slot formed in the section. When the outer section 2 is 30 extended, the latch 20 engages with the lower edge thereof, so as to prevent undue downward movement of the section 2, however, when it is desired to diminish the length of the staff, the latches 20 and 18 35 are successively depressed, thus permitting the inner section 3 to telescope within the outer section 2, thereby materially effecting a considerable reduction in the length of the staff. This feature may be further accomplished by detaching the handle section 4 40 from the lower end of the section 3. A bead is formed upon the lower end of the section 2 to limit its upward movement.

In view of the telescopic staff, and to decrease the size of the umbrella when it is 45 folded, it is necessary to form the ribs 11 into a plurality of pivotally connected members, the inner members 20' of which are pivoted to the ring 12 and have their outer 50 extremities connected by means of rule joints 21 to the outer members 22 thereof, with which the sliding elements 10 are associated. When the ribs are folded, as shown in Fig. 2, they extend in parallel relation and lie 55 adjacent to the staff 1, the rule joints 21 per-

mitting of a great reduction in the general length of the ribs.

The sliding elements 10 are provided with depending ears 27 to which are pivotally secured the outer ends of the braces 9, said elements being also provided with fixed leaf springs 28, the inner free ends of the latter being formed with openings 29. Thus, when the ribs are extended, the sliding elements 10 will be moved to positions 60 contiguous to the rule joints 21, in order that projections 30, formed upon the inner ends of the members 20' will engage with the openings 29 of said leaf springs, thereby effecting the locking of the braces to the 65 ribs when the umbrella is open.

From the foregoing it will be seen that the umbrella may be collapsed by depressing the latch 18 so as to permit the runner 7 to be drawn to its foremost position upon 75 the staff 1, thus drawing the ribs 11 inwardly, the catch 5 being actuated to retain the runner 7 in its retracted position. The outer section 2 is then telescoped upon the section 3 by actuating the latches 18 and 80 20, so that the sections 2 and 3 will assume the positions best shown in Fig. 4. After this operation has been completed, the outer members 22 of the ribs are folded to extend substantially parallel to the inner members 85 20', the sliding tubular elements 10 permitting of this function. Then by detaching the handle section 4 from the section 3, the umbrella will be reduced to its minimum size, forming a small and compact article. 90 A sliding cup 31 is carried by the handle section 4, and is adapted to be moved to a position to surround the lug of the catch 13, in order to prevent the latter element from being accidentally actuated.

Having described the invention what is 95 claimed as new and patentable is:

In an umbrella, a staff section, resilient catches located at spaced points thereon, a runner slidably mounted on the staff section 100 between the catches, said runner being cone shaped at its opposite ends, one cone shaped portion being provided at one end with an inturned shoulder and adapted to receive one catch and the other cone shaped portion adapted to move the other catch when brought in contact with the same.

In testimony whereof I affix my signature.

WILLIS K. MILLER.
